2 Claims. (Cl. 200—82)

(Granted under Title 35, U.S. Code (1952), sec. 266)

The invention described herein may be manufactured and used by or for the Government for governmental purposes without the payment to us of any royalty thereon.

This invention relates to electrical switches and more particularly to an electrical switch which is safely operable in the vicinity of flammable gas or fumes.

In the operation of some aircraft emergency escape systems, certain electrical connections have to be broken at a point where flammable gas may exist. Heretofore this has been done by means of a cable cutter. This is unsatisfactory for the reason that the severing of the connection may produce a spark by which the flammable gas is ignited. The present invention avoids this difficulty by the provision of an electrical switch which functions in response to pneumatic pressure and has its contact members separated in an enclosure from which the flammable gas is excluded.

The invention will be better understood from the following description when considered in connection with the accompanying drawing and its scope is indicated by the appended claims.

The single figure of the drawing illustrates a switch which includes a casing 10 having threaded onto one of its ends a sleeve 11 by which it is fixed to an insulation member 12. An insulation member 13 is movable within the casing 10 and has extending through it a contact member 14 which is arranged to engage a contact member 15 extending through the fixed insulation member 12. An O-ring seal 16 is between the casing 10 and the member 12 and a similar seal 17 is between the casing 10 and the member 13.

A housing 18 extends through the member 12 and is fixed thereto by means of an external ridge 19 and a snap ring 20, an O-ring seal 21 being provided between the member 12 and the housing 18.

Movable within the housing 18 is a piston 22 which has pivoted to its inner end a catch 23. This catch (1) is biased by a spring pin 32 so that it may be activated to rotate in a counterclockwise direction and (2) cooperates with the housing 18 and a member 24 to lock the switch in its closed position. The member 24 is fixed to the movable insulation member 13 by a nut 31a and is surrounded by a seal ring 25. A similar seal ring 26 is provided between the piston 22 and the housing 18.

Threaded on the outer end of the housing 18 is a gas inlet cap 27 against which a plunger 28 is held by a spring 29. When this plunger is in its illustrated position, the housing 18 and the piston 22 are interlocked by balls 30, the catch 23 is held against counterclockwise rotation by its engagement with the inner surface of the housing 18, and the movable insulation member 13 is held stationary

2

by an upwardly extending part 31 of the member 24 which engages the catch 23.

When the aircraft emergency escape system is to be operated, a gas pressure generated by an explosive cartridge is applied through the inlet 27 of the plunger 28. This compresses the spring 29 and moves the plunger 28 to a position where the balls 30 move to the interior of the piston 22 and release it from the housing 18. As the piston moves, the catch 23 moves with it to a point where it passes the end of the housing 18 and is free to rotate counterclockwise, thus releasing the members 24 and 13. Continued movement of the piston forces the member 13 away from the member 12 and separates the contact members 14 in the enclosure formed between these two members. Since this enclosure is sealed against leakage by O-rings 16, 17, 21 and 25 and 26, the switch is safely operated in the vicinity of flammable gas or fumes which could otherwise result in serious injury to the aircraft personnel.

20 We claim:

1. An electrical switch including a casing closed at one of its ends by a fixed insulation member having a first electrical conductor extending therethrough, an insulation member movable in said casing to form an enclosure between said insulation members and having a second electrical conductor extending therethrough, means fixed to said movable insulation member and having a flange extending transversely of said casing, a housing fixed to and extending through said fixed insulation member, said housing having at its inner end an opening receiving said flange, a piston movable in said housing, and a latch pivoted to the inner end of said piston and cooperating with said opening and said flange to lock said piston to said housing, said piston being movable to unlock said piston from said housing and to move said movable insulation member away from said fixed insulation member.

2. An electrical switch including a casing closed at one of its ends by a fixed insulation member having a first electrical conductor extending therethrough, an insulation member movable in said casing to form an enclosure between said insulation members and having a second electrical conductor extending therethrough, means fixed to said movable insulation member and having a flange extending transversely of said casing, a housing fixed to and extending through said fixed insulation member, said housing having at its inner end an opening receiving said flange, a piston movable in said housing, a latch pivoted to the inner end of said piston and cooperating with said opening and said flange to lock said piston to said housing, said piston being movable to unlock said piston from said housing and to move said movable insulation member away from said fixed insulation member, means for locking said piston to said housing, and gas pressure operated means for unlocking said piston from said housing and actuating said piston.
